DESIGN FOR A HEADLIGHT COVER GLASS

George M. Cressaty, Toledo, Ohio

Application August 18, 1933, Serial No. 49,052

Term of patent 14 years

To all whom it may concern:

Be it known that I, GEORGE M. CRESSATY, a citizen of the Republic of France, residing at Toledo, in the county of Lucas and State of Ohio, have invented a new, original, and ornamental Design for a Headlight Cover Glass, of which the following is a specification, reference being had to the accompanying drawing, forming part hereof.

In the drawing, in which I illustrate my new design,—

Figure 1 is a front elevational view of a headlight cover glass showing my new design;

Figure 2 is a vertical sectional view taken through the center of Figure 1;
Figure 3 is a side elevation of the cover glass;
Figure 4 is a front perspective view; and
Figure 5 is a rear perspective view.

I claim:—

The ornamental design for a headlight cover glass, substantially as shown.

GEORGE M. CRESSATY.
